UNITED STATES PATENT OFFICE

EDMUND L. MUNSON, OF MOUNT KISCO, NEW YORK

HOSPITAL BED

Application filed April 12, 1928. Serial No. 269,501.

My invention relates to improvements in hospital beds, and the object of my invention is to produce a bed in which a patient can be easily moved without injury or strain so as to reverse his position in the bed or to hold him at a desired inclination. In certain diseases it is often desirable to reverse or change the position of a patient, and this is generally difficult for the nurse or attendant and is also dangerous to the patient. It is also, as is well known, often desirable to have the patient lie at an inclination either for comfort, or drainage, or otherwise. My invention is intended to facilitate the changing of position, and to relieve the nurse or attendant from exertion. In carrying out my idea I have two bed parts or mattress supports, one of which is in a fixed vertical position but can turn over, and the other of which is rotatable with relation to the first, so that if the patient is lying on his back, for instance, on the top bed, the lower bed and mattress can by a simple mechanical movement be swung around over the patient and the bed on which he lies, then the mattress thus positioned can be gradually brought down upon the patient and swung back to its initial position, the upper bed turning on its pivot, and thus the patient will be lying on the second mattress and on his face instead of on his back. My invention is further intended to produce a positive, safe and easily operated means of accomplishing the foregoing and other movements which will appear more clearly in the description which follows.

Reference is to be had to the accompanying drawings forming a part of this specification, in which similar reference characters indicate corresponding parts in all the views.

Figure 1 is a plan view of a bed showing my improvements.

Figure 2 is a side elevation thereof.

Figure 3 is a broken cross section of the bed showing the normally lower bed swung to position above the upper bed.

Figure 4 is a view similar to Figure 3 but with the uppermost bed moved downward towards the one beneath.

Figure 5 is a cross section showing one of the beds at an inclination.

Figure 6 is a view similar to Figure 5 but with the two beds in different relation.

Figure 7 is a longitudinal sectional elevation of the complete bed.

Figure 8 is a cross section showing the two beds or mattress supports in normal position.

Figure 9 is a sectional detail showing means for turning and securing the beds.

Figure 10 is an elevation of the structure shown in Figure 9.

Figure 11 is an enlarged detail of one of the lower bed hangers and its adjusting means.

Figure 12 is a section on the line 12—12 of Figure 11, and

Figure 13 is a section on the line 13—13 of Figure 11.

The bedstead can be conventional, and I have shown it provided with a head board 10 and foot board 11 which are similar, and in the upper part of the bedstead is supported a bed having inner and outer frames 12 and 13 which are preferably of angle iron, and the inner frame 13 is hinged on one side as shown at 14 to the outer frame 12, and on the opposite side and upper part is a latch and button 15 which can be turned so as to prevent the bed or mattress frames from relative movement. On the other hand if it is desired to swing the inner frame so as to facilitate removing the mattress 24 or for other reasons, it can be done.

The frame 12 is centrally pivoted at its ends on a trunnion 16 (see Figure 12) which can be supported in a cross piece 10' on the head board 10, and a similar arrangement obtains on the foot board 11. The frames 12 and 13 can be secured against tilting on their pivots by any convenient means. For example the frame 12 is shown as lying opposite the bracket 17 at the bed ends, and secured to the bed frame, while a removable pin 18 extends through the bracket and into the part of the frame 12. If it is desired to tilt the upper bed and its mattress 24, the pins 18 can be removed and the bed tilted, and it can be secured at the desired inclination by means of the quadrant 19 secured to the frame 12. This has holes 20 therein, and these receive a pin 21 (see Figures 9 and 100

10) which also engage a bracket 22 which is hinged as shown at 23 to an adjacent part of the bed frame. Obviously other means might be used for fixing the inclination of the bed.

10 The lower or swinging bed has frames 25 and 26 which can be duplicates of the frames 12 and 13 already described, but the lower bed is suspended on a hanger by means of which it may be swung around to position above the frames 12 and 13. The hanger is suspended from trunnions 16, and I have shown it comprising plates 27 at the bed ends, and rigid on these plates are sprocket wheels 28 which connect by chains 29 with sprocket wheels 30 on the shaft 31 which runs parallel with one side of the frame 12, and can be turned by a removable crank 47 which will be hereinafter referred to as useable for another purpose.

25 When the swinging bed is in position above the tilting bed, as in Figures 3 and 4, it can be held against relative movement of the other bed by means of the latch 32 which is pivoted to the upper frame 12, and has a perforated end 33 through which a pin may be thrust and made to enter a hole 34 in one of the hanger plates 27.

30 The swinging bed represented by the frames 25 and 26 is movable back and forth with relation to the other bed, and to this end it has fixed nuts 35 thereon which fit the screws 36, and these are mounted in bearings 37 and 38 on the hanger plates 27, so that by rotating the screws the motion will be transmitted through the nut to the swinging bed and it can be moved back and forth as stated.

35 As a convenient means of actuating the screws I connect them at both ends with a single operating shaft, and it will be understood that this connection is shown by way of example, as other mechanical movements might just as well be substituted. As illustrated, the screws 36 at each end of the bed are provided with beveled pinions 39 which mesh with pinions 40 on the shafts 41 extending lengthwise of the bed and on opposite sides. The supporting connection be-

40 tween the screws and shaft can be by means of brackets 42. Transverse shafts 44 are provided with pinions 43 which also engage the pinions or gears 39, and the shaft 44 can be supported in brackets 45 attached to the plates 27. One end of the shaft 41 is squared to receive an operating crank 47, and this same crank can be applied to the squared end of the shaft 31 (see Figure 9) when the bed is to be swung.

45 When the crank is applied to the shaft 41 and turned, it will be seen that the motion will be transmitted to the screws 36 at both ends of the bed, and through the medium of the nuts 35 the swinging bed 25—26 can be

50 moved back and forth as desired with relation to the bed 12—13.

55 Each of the beds is provided with a mattress, the upper one having a mattress 24 and the lower a mattress 24', and the mattresses can be strapped or otherwise fastened to their frames, and the frames can of course be provided with conventional springs.

60 When the bed is in use, we will assume that the swinging bed is below the upper one on which the patient is lying, and it is desired to reverse the position of the patient. The operator applies the crank 47 to the shaft 31 and turns the crank, so that the motion is transmitted to the sprocket wheels 28, and the hanger plates 27 are thereby swung around so as to extend upward as shown in Figures 3 and 4, and the frame 25—26 will be in the position indicated with the mattress 24' on the under side. The crank is then applied to the shaft 41, and the mattress 24' moved down by means of the screws 36 until it is in position directly upon and against the patient. The two parts are locked together by the latch 32, the pins 18 are removed, and the shaft 31 is turned back in the opposite direction so as to bring the swinging bed immediately below the upper one as in Figure 5, and the patient will then be lying on the mattress 24' and in exactly the reverse position to his former position on the mattress 24. The shaft 41 can then be turned so as to lower the swinging bed represented by the frames 25—26 to the desired position, and the upper mattress can be swung out of the way so as to leave desired clearance.

65 With the patient is on the upper bed, that is on the mattress 24, he can be easily placed at a desired inclination by removing the pins 18, rotating the frame 12 slightly on the trunnions 16, and fixing the position by means of the quadrant 19 and pins 21, as already described.

70 Thus it will be seen that I have provided a very secure and easy means of changing the position of a patient without wrenching or exerting him in any way, and with ease to the operator.

I claim:—

75 1. A structure of the kind described comprising a reversible bed, hangers pivoted at the ends of the reversible bed, a second bed carried by the hangers, means for swinging the hangers and the second bed to a position either above or below the reversible bed, and means for locking the swinging bed against swinging movement.

80 2. A structure of the kind described comprising a reversible bed, hangers pivotally supported at the ends of the reversible bed, a second bed carried by the hangers, means for swinging the hangers and the bed which they carry to a position above or below the first mentioned bed, and means for adjusting the swinging bed up and down on its hangers.

3. A structure of the kind described comprising a reversible bed, hangers pivotally supported at the ends of the reversible bed, a second bed carried by the hangers, means for 5 swinging the hangers to position the second bed above or below the reversible bed, and a gear and screw mechanism for adjusting the second bed up and down on its hangers.
4. A structure of the kind described comprising a bed frame, a bed pivoted on trunnions in the frame, hangers mounted on the trunnions, a second bed carried by the hangers, a gear mechanism for swinging the hangers and their bed to carry the latter above or 10 below the pivoted bed, and means for adjusting the swinging bed up and down on its hangers.
5. A structure of the kind described comprising a bed pivoted to turn on its own axis, 15 a swinging bed, means for swinging said swinging bed to a position above or below the first-mentioned bed, means for moving the beds to or away from each other, and means for rotating said beds as a unit.
6. A structure of the kind described comprising a reversible bed pivoted to turn on its 20 own axis, a swinging bed, means for swinging said swinging bed to a position either above or below the reversible bed, means for adjusting the distance between the swinging bed and the reversible bed, and means for rotating said beds as a unit.
7. A structure of the kind described comprising a reversible bed pivoted at the ends 25 to turn on its own axis, a second bed supported on hangers, and means for swinging the hangers and the second bed to a position above or below the first-mentioned bed, and means for rotating said beds as a unit.
8. In a hospital bed for reversing the 30 position of a patient, a reversible bed pivoted to turn on its own axis, a second bed supported on hangers, said hangers swinging on the axis of the reversible bed, and means for 35 adjusting the hangers and the second bed to a position above or below the first-mentioned bed.

In testimony whereof, I have signed my name to this specification this 10th day of April, 1928.

EDMUND L. MUNSON.
